PACKER FOR OIL WELLS

Application filed January 26, 1929. Serial No. 335,288.

My invention relates to packing devices, and more particularly to a novel packer for sealing two adjacent members in fluid-tight relationship.

5 In the oil-well drilling art, as well as in other arts, it is desirable to be able to seal two adjacent members in fluid-tight engagement. It is often necessary to effect this seal at a point which is inaccessible, and it thus 10 becomes necessary to use a special type of packer which may be operated from a remote point. Various types of packers have been devised, but these packers are open to the objection that they have a swabbing action 15 when the seal is to be effected below the body of a fluid. Thus, in the oil-well drilling industry it is frequently necessary to seal concentric pipes or tubings at a point below the level of a fluid in these tubings.

20 It is an object of this invention to provide a packer which will not exert a swabbing action either before being set or after being released when this packer is moved relative to the member it is adapted to engage in fluid-tight relationship.

A further object of this invention is to provide a novel packer having a plurality of annular packing members and a plurality of spacing rings therebetween.

30 Still another object of this invention is to provide such a packer in which the spacing rings provide complementary surfaces which are engageable with each other when the packing members become sufficiently compressed or upon the failure of any packing member, thereby insuring an effective seal at all times.

Another object of this invention is to provide a novel form of packing member having 40 a soft core around which is wound a cloth member, this member being preferably wound on a bias.

Another object of this invention is to provide a novel packer which is locked in retracted position until such a time as it is in a desired position. This is an extremely important feature inasmuch as certain packers at present in use have a tendency to be set prematurely, due to the fluid pressure exerted 45 on the packer when the packer is moved.

Still another object of this invention is to provide a novel packer having a floating foot member which engages the packing member and is engaged by suitable jaw members.

Further objects and advantages of this invention will be made evident hereinafter. 55

Referring to the drawings in which I have illustrated a preferred embodiment of my invention,—

Fig. 1 is a view, partially in section, illustrating the packer of my invention when being lowered into a tubing, and before being set therein. 60

Fig. 2 is a view, partially in section, illustrating the packer of my invention after being set. 65

Fig. 3 is a similar view illustrating the packer in released position.

Figs. 4, 6, and 7 are sectional views taken on corresponding lines of Fig. 3. 70

Figs. 5 and 8 are sectional views taken on corresponding lines of Fig. 2.

Fig. 9 is a perspective view of one of the slips of my invention.

Fig. 10 is a diagrammatic view illustrating 75 a section of a packing member of my invention.

Fig. 11 is an enlarged view illustrating the novel cooperation between the spacing rings and the packing rings of my invention. 80

Referring particularly to Figs. 1, 2, and 3, the packer of my invention is adapted to seal a primary or inner member 12 relative to a secondary or outer member 13. This outer member may be in the form of tubing as 85 illustrated in Fig. 1, and the inner member may be in the form of a tubing extending concentric with the outer member 13.

Secured to the lower end of the inner member 12 is a head member 15 to which are secured inner and outer sleeves 16 and 17 which may be secured at their lower ends by a connecting member 18, and the sleeve 16 may extend downward from this connecting member, as indicated at 19, if desired. While 90 I have illustrated two sleeves 16 and 17, this particular combination is not essential to the operativeness or novelty of this invention. On the smaller sized packers only one sleeve 95 is ordinarily utilized.

Adapted to slide on the sleeve 17 is a foot member 20 providing a channel 21 therein communicating with a hole 22. Spaced between the head member 15 and foot member 20, and surrounding the sleeve 17, is a plurality of spacing rings 24, the inner diameter of each spacing ring being larger than the outer diameter of the sleeve 17 so as to provide a by-pass 25 therebetween. This by-pass is bridged at intervals by legs 26 which extend inward from each spacing ring 24 into sliding engagement with the sleeve 17, thus keeping the packing ring concentric with the axis of the sleeve.

The head member 15, the foot member 20, and the spacing rings 24 have complementary surfaces which are adapted to come into engagement to form a fluid-tight metal-to-metal seal. Thus, the lower portion of the head member 15 is provided with a primary surface 28, while the foot member 20 is provided with a secondary surface 29. These surfaces are preferably formed on an angle of 45° relative to the axis of the sleeve 17.

Primary and secondary surfaces 30 and 31 are formed on each of the spacing rings 24, the surface 30 being complementary to the primary surface 28 of the head member 15, while the secondary surface 31 is complementary to the secondary surface 29 of the foot member 20. The surfaces 30 and 31 are formed at an angle of 45° so as to correspond to the angle of the surfaces 28 and 29. It should thus be apparent that the primary surface 30 of each spacing ring 24 is complementary to the secondary surface 31 of the adjacent spacing ring, and by sufficiently moving the foot member 20 toward the head member 15 the spacing rings 24 will come into engagement with each other and with the head and foot members. This condition is shown in Fig. 2, at which time the by-pass 25 is closed at its upper end by the engagement between the primary surface 28 of the head member 15 and the primary surface 30 of the uppermost spacing ring 24. The lower end of this by-pass communicates with the channel 21 of the foot member, and with the hole 22 therethrough.

Spaced between each of the spacing rings 24, and also between the head and foot members and these rings, is a plurality of packing members in the form of packing rings 33. Each of these rings is formed with a central core 34 of soft flexible material, preferably soft rubber or sponge rubber, this core being annular in shape and circular in cross-section. A cloth member 35 is wound around the core 34 on a bias so that the individual threads forming the cloth member spiral around the core 34 rather than extending parallel to the axis of this core. The cloth member 35 and core 34 are then vulcanized by well-known processes. This particular type of packing ring permits a material

amount of expansion and compression without danger of the strands of the cloth member 35 failing. Furthermore, such a packing ring will not become vulcanized against the casing after being set some time and after being subjected to the high temperatures sometimes experienced in situations where the use of a packer is necessary.

The packing rings 33 are of such a diameter that when the packer is being lowered into place in a position shown in Fig. 1, the periphery of each packing ring engages the secondary surface 31 of the spacing ring 24 immediately thereabove and rests on a radial surface 36 of the spacing ring immediately therebelow. As the foot member 20 is moved toward the head member 15, the packing rings roll on the secondary surfaces 31 of the packing rings, and come into engagement with a tapered surface 37 of each ring, this tapered surface terminating in a flange 38. Similarly, the uppermost packing ring 33 rolls from the primary surface 28 onto a tapered surface 39 of the head member 15.

The tapered surfaces 37 and 39 have been termed tertiary surfaces for the purpose of distinguishing these surfaces from the primary surfaces 28 and 30 and the secondary surfaces 29 and 31. I prefer to form the tertiary surfaces 37 and 39 on an angle of 30° relative to the axis of the sleeve 17, so that the tertiary surfaces are at a steeper angle than the primary and secondary surfaces.

As the foot member 20 moves further toward the head member 15 the packing rings 33 are moved outward into engagement with the outer member 13, due to their engagement with the tertiary tapered surfaces 37 and 39. After coming into engagement with this outer member the packing rings are deformed, as best shown in Figs. 2 and 11. I prefer to so proportion the packing rings 33 that the head member 15 and foot member 20 may come into surface contact with the spacing rings 24 when the packer is set, thus insuring a double seal; first, a metal-to-metal seal between the head and foot members and the spacing rings; and, second, a seal between the packing rings 33 and the outer member 13.

If, now, the foot member 20 be moved away from the head member 15, the packing rings 33 will assume a position shown in Fig. 3, but will remain distorted. These rings 33 and the spacing rings 24 will thus not fill the space between the foot member 20 and the head member 15, thus opening the by-pass 25 at its upper end, as best shown in Fig. 3.

If, now, the packer is to be moved relative to the outer member 13, no swabbing action will take place, any fluid above or below the packer being displaceable through the by-pass 25 in a direction depending upon the

direction of the movement of the packer relative to the outer member 13.

The movement of the foot member 20 relative to the head member 15 is accomplished by means of an operating mechanism, best illustrated in Figs. 1, 2, and 3. Referring to these figures, a slip cage 45 is slideable relative to the sleeve 17, and provides a pair of hook members 46 which normally engages

10 a pair of diametrically opposite pins 47 to hold this slip cage in the position shown in Fig. 1. Extending upward from, and welded relative to, the slip cage 45 is a plurality of spring arms 49 which forms a part of a

15 plurality of slips 50, these slips having jaws 51 at their upper ends. The outer surface of each jaw is provided with teeth 52, and the inner surface of each jaw is frusto-conical in shape and defines a tapered surface 53.

20 These tapered surfaces of the slips correspond to the taper of the foot member 20 when the jaws are in a position shown in Fig. 2. When the jaws are in the position shown in Figs. 1 and 7, the contour of the

25 tapered surface 53 does not correspond to the tapered contour of the foot member 20. Thus, in Fig. 7 I have illustrated the jaws in the lower position wherein the surface 53 engages the foot member 20 in line contact

30 instead of surface contact. This line of contact is indicated by the line A—A of Fig. 9, and is also illustrated in Figs. 7 and 8.

A hook 55 is formed on the lower portion of each jaw 51, as best illustrated in Fig. 9, 35 this hook being bisected by the line A—A.

The inner surface 56 of the hook 55 is formed continuous with the tapered surface 53 so that when the jaw 51 is in its upper or engaged position shown in Fig. 2, the surface

40 56 engages the tapered surface of the foot member 20. When the slip 50 is in its lower position, indicated in Fig. 1, at which time the hook members 46 engage the pins 47, the hooks 55 of each slip 50 enter a groove

45 57 formed by a ledge 58 extending outward from the bottom of the foot member 20. The groove 57 is formed on an acute angle so that the slips are locked in a retracted position due to the engagement between the

50 hook members 46 and the pins 47 so that the jaw members cannot move radially outward until the hook members 46 disengage the pins 47.

I prefer to form the arms 49 so that they 55 exert an inward force on the jaws 51, thus tending to maintain these jaws in engagement with the foot member 20. A spring 60 is secured to each arm 49 and is adapted to pressurally engage the outer member 13 in 60 a manner to retard the movement of the slip cage 45.

The operation of my invention is as follows:

Before lowering the packer into the outer 65 member 13 the hook members 46 are hooked

relative to the pins 47, thus causing the packer to assume the position illustrated in Fig. 1. The packer is then lowered into position and any fluid in the outer member 13 is displaced around the packing rings 33 during this lowering movement, due to the fact that the outer periphery of each of these rings is smaller than the inner diameter of the outer member 13.

When the packer is in the desired position, the operator turns the inner member 12 to the left, as viewed from above, thus releasing the pins 47 from the hook members 46. The inner member is then lowered. During this lowering movement the slip cage 75 45 is no longer restrained by the pins 47, and the springs 60 hold this slip cage relative to the outer member 13. Thus, any downward movement of the inner member 12 moves the jaws 51 upward on the foot member 20 into engagement with the outer member 13. A further downward movement of the inner member 12 compresses the packing rings 33 into a position as shown in Fig. 2, at which time an effective seal is 80 produced, as previously described. When it becomes desirable to release the packer, the inner member 12 is moved upward into a position shown in Fig. 3, thus releasing the jaws 51 and separating the head and foot members 15 and 20. At this time the pins 47 may be made to engage the hooks 46 by turning the inner member 12 a quarter turn to the right.

It will be noted from Fig. 3 that the packing rings receive a permanent deformation after being set. Oftentimes, the outer diameter of these rings is very close to the inner diameter of the outer member 13 due to this deformation. As the packer is moved upward any fluid above the packer must pass through or around this packer. To prevent any swabbing action, I have provided the by-pass 25 which is at this time completely open, as best shown in Fig. 3, thus allowing the fluid to be displaced, as indicated by the arrows 65 of Fig. 3.

It should be apparent that my packer is not limited to the oil-well drilling art, but finds utility in any art where it is desired to seal a primary and secondary member in fluid-tight relationship relative to each other. The double seal provided by the engagement between the packing rings 33 and the outer member 13, together with the metal-to-metal seal provided by the engagement of the primary and secondary surfaces of the head member 15, foot member 20, and spacing rings 24, is an important part of this invention. Thus, if any particular packing ring should fail, the rings above and below would not be subjected to excessive strain even if a large pressure difference were maintained on opposite ends of the packer. This is due to the engagement between the pri- 125 130 135 140 145 150 155 160 165 170 175 180 185 190 195 200 205 210 215 220 225 230 235 240 245 250 255 260 265 270 275 280 285 290 295 300 305 310 mary and secondary surfaces 30 and 31 of the spacing rings 24 adjacent this particular packing ring.

Furthermore, the particular form of packing ring illustrated has been found to be extremely satisfactory in this type of packer, and my invention is not limited to the use of this packing ring in the particular packer illustrated inasmuch as this ring finds utility 10 in various other capacities.

I claim as my invention:

1. In a packer, the combination of: a sleeve; a head member on said sleeve, said head member providing a primary surface; 15 a foot member movable on said sleeve toward said head member, said foot member providing a secondary surface; a plurality of flexible packing rings around said sleeve and between said head and foot members; and a 20 spacing ring between adjacent packing rings, said spacing ring providing primary and secondary surfaces which are complementary to said primary and secondary surfaces of said head and foot members and engageable therewith after said packing rings are sufficiently compressed, and said packing and spacing rings being formed larger in diameter than said sleeve in a manner to provide a by-pass opening therebetween.
2. A combination as defined in claim 1 in which said foot member has a by-pass hole communicating with said by-pass opening.
3. In a packer, the combination of: a sleeve; a head member on said sleeve, said head member providing a primary surface; 25 a foot member movable on said sleeve toward said head member, said foot member providing a secondary surface; a plurality of flexible packing rings around said sleeve and between said head and foot members; and a plurality of spacing rings, one of said rings being positioned between each of said packing rings, each of said spacing rings including primary and secondary surfaces complementary to said primary and secondary surfaces of said head and foot members, said sleeve and said spacing rings being so relatively formed that by-pass openings are formed between said sleeve and said spacing rings.
4. In a packer for sealing the space between a primary and a secondary member, the combination of: a tapered foot member movable relative to said primary member; packing means compressed into engagement with said secondary member by said movement of said foot member; a slip cage movable relative to said primary member; slips carried by said slip cage and movable along said foot member into engagement with said secondary member; means for detachably securing said slip cage relative to said primary member; and means for locking said 65 slips relative to said foot member when said

slip cage and said primary member are detachably secured together.

5. In a packer of the class described, the combination of: a supporting structure; a plurality of packing members on said supporting structure; compressing means whereby said packing members are caused to occupy a sealing position; and a spacing member placed between adjacent packing members and forming a passage between said supporting structure and said packing members after 70 said packing members have been caused to occupy a sealing position.

6. In a packer of the class described, the combination of: a supporting structure; a plurality of packing members on said supporting structure; compressing means whereby said packing members are caused to occupy a sealing position; and a spacing member placed between adjacent packing members 80 and forming a passage between said supporting structure and said packing members after said packing members have been caused to occupy a sealing position, said spacing member having actual contact with said compressing means when said packing members are in sealing position, to separate said packing members from said passage.

7. In a packer of the class described, the combination of: a supporting structure; a 95 plurality of packing members on said supporting structure; compressing means whereby said packing members are caused to occupy a sealing position; and a spacing member placed between adjacent packing members 100 and forming a passage between said supporting structure and said packing members after said packing members have been caused to occupy a sealing position, said spacing member being separated from said compressing means by said packing members prior to the operation of the compressing means and said spacing member having actual contact with said compressing means when said packing members are in sealing position, to separate 105 said packing members from said passage.

8. In a packer for sealing the space between a primary and a secondary member, the combination of: a head member on said primary member; a foot member movable on said primary member relative to said head member; and means comprising a plurality of flexible packing members compressible between said head member and said foot member and a spacing member between adjacent packing members, said spacing member having surfaces complementary to surfaces of said head and said foot members, certain of which come into engagement upon a sufficient yielding of one of said packing members, said packing members and said spacing members of said packing means being so formed as to provide a by-pass opening between the exterior face of said primary member and the interior face of said packing means.

9. In a packer for sealing the space between a primary and a secondary member, the combination of: a head member on said primary member; a foot member movable on said primary member relative to said head member; a plurality of flexible packing members compressible between said head member and said foot member; and a spacing member between adjacent packing members, said 10 spacing member providing a passage around said primary member and within said packing member after said packing members are compressed by said head and foot members.
10. In a packer for sealing the space between a primary and a secondary member, the combination of: a tapered foot member movable relative to said primary member, said tapered foot member having a notch formed therein; packing means compressed 15 into engagement with said secondary member by said movement of said foot member; a slip cage movable relative to said primary member; slips carried by said slip cage and movable along said foot member into engagement 20 with said secondary member; means for detachably securing said slip cage relative to said primary member; and engaging means on said slips adapted to engage in said notch when said slips are in retracted position.
11. A packer including: a supporting structure; a holding means; means for releasably retaining said holding means from longitudinal movement on said supporting structure; a slip carried by said holding 25 means; expanding means for said slip; packing means adapted to be actuated by movement of said expanding means on said supporting structure; and means for locking said slip to said expanding means when said 30 slip is in retracted position whereby to prevent movement of said expanding means on said supporting structure.
12. In a packer for sealing the space between a primary and a secondary member, the combination of: a tapered foot member supported by and movable on said primary member; a slip cage movable relative to said primary member; slips carried by said slip cage and movable along said foot member 35 into engagement with said secondary member; means for detachably securing said slip cage relative to said primary member; and means for locking said slips relative to said foot member when said slip cage and said 40 primary member are detachably secured together.
13. In a packer for sealing the space between a primary and a secondary member, the combination of: a tapered foot member supported by and movable on said primary member; a slip cage movable relative to said primary member; slips carried by said slip cage and movable along said foot member into engagement with said secondary member; means for detachably securing said slip cage 45
- relative to said primary member; and means for locking said slips relative to said foot member when said slip cage and said primary member are detachably secured together, said slip locking means being released upon longitudinal movement of said slips. 50
14. In a packer for sealing the space between a primary and a secondary member, the combination of: a tapered foot member movable relative to said primary member; packing means compressed into engagement with said secondary member by said movement of said foot member; a slip cage movable relative to said primary member; slips carried by said slip cage and movable along said foot member into engagement with said secondary member; means for detachably securing said slip cage relative to said primary member; and means for preventing said foot member from moving away from said slips while said slip cage is locked to said primary member. 55
15. In a packer for sealing the space between a primary and a secondary member, the combination of: a tapered foot member supported by and movable on said primary member; a slip cage movable relative to said primary member; slips carried by said slip cage and movable along said foot member into engagement with said secondary member; means for detachably securing said slip cage relative to said primary member; and means for preventing said foot member from moving away from said slips while said slip cage is locked to said primary member. 60
- In testimony whereof, I have hereunto set my hand at Los Angeles, California, this 21st day of January, 1929.
- GERHARD MEYER.

CERTIFICATE OF CORRECTION.

Patent No. 1,859,744.

May 24, 1932.

GERHARD MEYER.

It is hereby certified that error appears in the printed specification of the above numbered patent requiring correction as follows: Page 4, line 117, claim 8, before the word "means" insert the word packing; and that the said Letters Patent should be read with this correction therein that the same may conform to the record of the case in the Patent Office.

Signed and sealed this 12th day of July, A. D. 1932.

(Seal)

**M. J. Moore,
Acting Commissioner of Patents.**
